REGENERATING MERCAPTAN SOLVENT

Jack H. Krause and Theodore B. Tom, Hammond,
Ind., assignors to Standard Oil Company, Chi-
cago, Ill., a corporation of Indiana

Application June 25, 1949, Serial No. 101,476

3 Claims. (Cl. 196—32)

1

This invention relates to the separation of mercaptans by extraction from hydrocarbon distillates such as gasoline, kerosene and heater oil obtained from the distillation of crude petroleum and cracking still distillates. More particularly the invention relates to the regeneration of caustic alkali solutions employed in the extraction process. The invention is illustrated by a drawing which shows in Figure 1 a diagram of an apparatus suitable for carrying out the process. Figure 2 shows the effect of temperature on extraction efficiency. Figure 3 is a graph showing the behavior of a KOH-methanol solution on removal of methanol by distillation.

This application is a continuation-in-part of our application Serial No. 45,538 filed August 21, 1948, now abandoned.

In the extraction of mercaptans with solutions of alkali metal hydroxides, it has long been found that the solubility of mercaptans in the caustic solution is substantially increased by employing methanol, ethanol, isopropyl and normal propyl alcohols in the solution. Methanol in particular has numerous advantages partly because of its lower oil solubility and partly because of its lower boiling point making it easier to recover. Solutions of various compositions have been employed including substantially anhydrous sodium hydroxide in methanol on the one hand and relatively dilute solutions of sodium hydroxide in water containing varying amounts of methanol on the other hand. After contacting the sour hydrocarbon oil, the solution has generally been regenerated by distilling off the methanol and the mercaptans employing steam to hydrolyze the mercaptides dissolved in the caustic solution. After separating the methanol from the mercaptans in the distillate, it has been recombined with the regenerated caustic solution for further use in the extraction of sour oil.

In the extraction of heavier stocks such as kerosene and heater oil, regeneration of the caustic solution has been found to be more difficult than in the case of lighter stocks because of the difficulty of distilling the high molecular weight mercaptans from the caustic solution. The usual method of removing the mercaptans from the caustic by steaming at elevated temperature requires much larger amounts of steam in the case of heavier mercaptans, thereby substantially increasing the cost of the operation. High regeneration temperatures cannot be used because the mercaptans break down in the presence of caustic, forming alkali metal sulfides which are troublesome to handle and which represent a loss of alkali metal hydroxide from the process. Furthermore, higher temperatures increase corrosion problems. Unless the caustic is substantially free of mercaptans in the regeneration operation, contaminating mercaptans

2

will be returned to the hydrocarbon oil being treated when the caustic solution is recycled. Thus a high mercaptan re-entry value limits the extent to which mercaptans can be extracted from the oil and results in a product which is unacceptable for marketing, it being generally desirable to reduce the mercaptan content of the oil to a value below 10 mercaptan number, preferably about 1 to 5 mercaptan number. The mercaptan number is the milligrams of mercaptan sulfur per 100 ml. of oil and is usually determined by titration with a standardized copper salt solution. An oil having a mercaptan number of less than 1 is generally considered to be "sweet."

It has been found that the extraction of higher boiling stocks such as kerosene and heater oil containing higher molecular weight mercaptans is considerably improved by incorporating in the extraction solution in addition to methanol the alkali metal salt of an acidic organic solvent, preferably a heavy alkyl, phenol, cresol or xylene. Napthenic acids can also be employed. It is important from the standpoint of operating procedure that the alkali metal salt of the acid reagent be a liquid or be easily liquefied by heat. When present in the solution to the extent of about 2 to 20 per cent by weight, the alkyl phenols, hereinafter referred to as phenols, form phenolates with the caustic alkali and substantially increase the solubility of mercaptans in the alcoholic caustic solution.

Certain petroleum oil fractions contain phenols in small amounts, e. g. 0.1 per cent, which are removed from the oil by the methanol-caustic solution along with the mercaptans and these have been found to exert a beneficial influence on the mercaptan separation, particularly when treating the higher boiling hydrocarbon distillates. Phenols obtained from gasoline have a lower boiling range than those obtained from heavier oils such as heater oil. The following distillation analysis gives the boiling range of two typical examples of such phenols:

45

Distillation analysis—ASTM

	Phenols from Gasoline	Phenols from Heater Oil
Initial Boiling Point.....	372	374
10% Distilled.....	385	400
50% Distilled.....	392	446
90% Distilled.....	412	508
Maximum Boiling Point.....	446	553

55

One object of our invention is to reduce the mercaptan re-entry value of the regenerated caustic solution. Another object of our invention is to provide a method for regenerating caustic methanol solutions containing high

60

molecular weight mercaptans difficult to eliminate from the solution by vaporization. Another object of our invention is to eliminate the use of steam in the regeneration of mercaptans containing caustic solutions. Still another object of our invention is to effect the recovery of caustic-methanol solutions at moderately low temperatures without the formation of undesirable color bodies which contaminate the oil undergoing treatment. A still further object of our invention is to simplify the recovery of mercaptan-contaminated caustic solutions and thereby effect substantial economies in the operation.

According to our invention, the foregoing objects are attained by maintaining a ratio of caustic alkali and water in the solution within a critical range corresponding to a concentration of 50 to 65 per cent and by maintaining close control of methanol concentration. Because of the tendency of sodium hydroxide to crystallize in solutions of this concentration, we have found that caustic soda is unsatisfactory for use in our process and we accordingly employ a solution of potassium hydroxide. The amount of methanol employed in the solution is usually about 15 to 60 volumes per 100 volumes of aqueous KOH solution, a typical solution containing about 60 per cent KOH in water and 30 volumes of methanol per 100 volumes of aqueous KOH solution.

We have discovered that when operating within this range of caustic concentration, most of the methanol can be distilled from the solution at moderately low temperatures substantially free of mercaptans, apparently as a result of the combined effect of the high KOH concentration, the low temperature of distillation, and the absence of steam ordinarily employed for the purpose of hydrolyzing the alkali mercaptides. For this purpose, it is desirable to employ temperatures in the range of about 150 to 200° F. Higher temperatures may be used, e. g., 200 to 400° F., but usually cause development of color bodies in the recovered caustic solution, making it brown. When using reduced pressure of about 50 mm. mercury, it is preferred to operate at a temperature in the range of about 130-180° F.

Altho the boiling point of methanol is 148° F., it is not practicable to distil off all the methanol at this temperature because of the effect of the KOH in depressing the vapor pressure of the methanol. Accordingly, we prefer to employ reduced pressure in the methanol distillation step, a pressure of the order of 10 to 100 mm. mercury, absolute, being satisfactory. In general, it is desirable to distil off part of the methanol at atmospheric pressure and employ reduced pressure in a second distillation stage. For the practical operation of our process, it is necessary to reduce the methanol concentration below about 18 volumes per 100 volumes of aqueous caustic solution and best results are obtained by reducing the methanol concentration below about 15 volumes per 100 volumes of aqueous caustic solution. When operating at 50 mm. pressure at a temperature of 172° F., the methanol concentration of a 59 per cent KOH solution was reduced from 25 volumes to less than 5 volumes per 100 volumes of 59 per cent aqueous KOH solution.

We have discovered that, when using highly concentrated solutions of KOH, the removal of at least one-third of the methanol from the KOH-methanol solution causes the dissolved mercaptans to separate from the solution as a

separate phase, usually in the form of a liquid or an emulsion which floats on the surface of the strong aqueous KOH solution. When employing aqueous KOH solutions in the concentration range of about 50 to 65 per cent, the solubility of the mercaptans in the solution after removal of methanol is so low that the KOH solution is suitable for recycling in the process without further treatment and no stripping of mercaptans or heating to high temperature is required.

This is well illustrated by the effect of removing methanol from a solution of 55 per cent KOH in water containing 25 volumes of methanol per 100 volumes of aqueous solution. This solution was saturated with mercaptans by contacting it with a sour heater oil from West Texas crude having a mercaptan number of 69. The mercaptan number of the extract was 239. After distilling off 15 volumes of methanol, the residue solution was allowed to separate into a mercaptide layer and a caustic layer, and the caustic layer was found to have a mercaptan number of 4.3.

Referring to Figure 1, sour hydrocarbon oil, for example heater oil of 40 A. P. I. gravity having a 10 per cent point—ASTM—of 360° F. and 90 per cent point of 527° F., is introduced to the process by line 10 and contacted with an alkaline solution in mixer 11 and settler 12 for the removal of H₂S and CO₂. The alkaline solution, for example dilute caustic soda, can be recycled to the mixer by line 13. The washed heater oil free of H₂S passes by line 14 to mixer 15 which is the initial stage of contacting with KOH-methanol solution introduced by line 16. The mixture from 15 is settled in 17 from which caustic-methanol solution can be recycled by line 18 to mixer 15 to increase the efficiency of contact with the hydrocarbon stock. The volume of solution introduced by line 16 is generally about 5 to 20 per cent of the volume of the oil treated, 10 per cent being a satisfactory amount, altho we may use proportions of caustic solution to oil as low as 1 to 50 by volume, depending on the character of the oil treated and the amount of mercaptans contained therein.

From settler 17 the hydrocarbon oil passes by line 19 to mixer 20 and settler 21 where it is contacted with KOH-methanol introduced by line 22. Again the ratio of solution to oil in mixer 20 can be increased by recycling the aqueous phase from settler 21, using lines 23 and 24 for this purpose. A suitable solution composition for charging to mixer 20 by line 22 is about 25 volumes of methanol per 100 volumes of aqueous 55 per cent KOH. The temperature of contact is usually about 80 to 100° F., preferably 90° F. Higher temperatures up to about 125° F. may be employed but result in somewhat lower mercaptan solubility in the caustic solution, while temperatures below 80° F. may produce solidification of the KOH solution, particularly at the higher concentrations. The effect of temperature on extraction efficiency is illustrated by the curve in Figure 2, showing removal of mercaptans from heater oil by two successive treats with KOH-methanol solution (100 volumes 59% KOH, 25 volumes methanol), which were equivalent to four countercurrent stages.

Altho the drawing shows only two treats of caustic-methanol, any number of stages may be employed, e. g. three to five stages, depending upon the economics of the process wherein installation costs, operation and maintenance are

balanced against extraction efficiency. Instead of stage contacting we may employ a contacting tower wherein the caustic-methanol solution is introduced at the top of the tower and the hydrocarbon oil at the bottom, countercurrently contacting throughout the tower, the number of stages in this case being infinite theoretically.

From the second stage in settler 21, the oil is conducted by line 25 to wash mixer 26 thence to settler 21, water being introduced by line 28 for the recovery of small amounts of methanol dissolved in the hydrocarbon oil, e. g., usually about 0.2 to 2 per cent before washing. From washing stage 27 the water may be recycled thru mixer 26 by line 29. The finished oil substantially free of methanol and mercaptans is withdrawn from the process by line 30.

Regeneration of the spent caustic solution is effected by conducting the solution by line 31 to heat exchanger 32 and thence thru heater 33 to flash tower 34. In heater 33 the caustic solution is preferably heated to a temperature of about 130° F. to 300° F. The pressure on the heated caustic solution which may be in the range of about 10 to 100 p. s. i. is suddenly reduced by valve 35 and vaporization of the methanol results. Methanol vapors pass upwardly thru tower 34 and methanol may be refluxed by cooling coil 36. Methanol vapors are conducted by line 37 thru exchanger 32 and thence to cooler 38 where the methanol is condensed for recycling in the process. Tower 34 may be operated at a reduced pressure maintained by vacuum pump 39 connected by vacuum line 40 to methanol receiver 41, the methanol being withdrawn by line pump 42 and line 43 to the regenerated caustic solution line 44. If tower 34 is operated at atmospheric pressure, however, receiver 41 may be by-passed by a suitable by-pass line 45 as indicated.

The heating coil 46 in the base of tower 34 may be employed to assist in elimination of methanol from the caustic solution if the amount eliminated by flashing is not sufficient for the purpose. From the base of the tower the caustic solution is withdrawn by line 47 leading to separator 48 equipped with suitable baffles for separation of the insoluble mercaptides which form as a layer on the surface of the regenerated KOH. Inasmuch as substantially no water is removed with the methanol in tower 34, the concentration of KOH in separator 48 is substantially the same as that employed in the original extraction solution, for example 55 per cent. This solution now containing very little mercaptans, as indicated by a mercaptan number of only 5, is recycled to the extraction process by pump 49 and line 44 in combination with the recovered methanol.

The separated potassium mercaptides are withdrawn from separator 48 by line 50 and may be discarded from the system, if desired, or employed for various purposes. However, it is usually desirable to treat the mercaptide fraction further for the recovery of KOH and small amounts of methanol contained therein. This is readily accomplished by adding water by line 51 while forcing the mercaptides by pump 52 into mixer 53. Sufficient water is introduced to produce a KOH concentration of about 10 to 40 per cent resulting in hydrolysis of the mercaptides and separation of the oily mercaptan layer in separator 54, which is withdrawn by line 55.

The aqueous KOH solution is withdrawn by line 56 leading to still 57 which may be an externally fired kettle operated either continuously or batchwise, preferably the latter, considering

that the amount of KOH to be recovered is but a small fraction of the total amount of KOH employed in the extraction process. In still 57 the water containing a small amount of methanol and mercaptans is removed by line 58 leading to condenser 59 and receiver 60 where mercaptans are separated and withdrawn by line 61, the water being recycled by pump 62 and line 63 back to mixer 53. Methanol accumulating in the recycle water may be recovered if desired, by a conventional methanol fractionator not shown.

The KOH solution in still 57 is concentrated to about the same concentration as that originally employed in the extraction solution, e. g. 50 to 65 per cent. However, a higher concentration may be desirable to offset the accidental influx of water into the system, in which case the KOH solution in 57 may be concentrated to 75 or 80 per cent. The hot solution can be transferred by line 64 and pump 65 to caustic recycle line 44, or it may be conducted by line 66 to the spent caustic stream charged to evaporator 34.

Phenols contained in the oil undergoing extraction accumulate in separator 48 in the form of potassium phenolates. These are finally eliminated from the system with the mercaptans by line 55. The presence of phenols has a favorable effect on the separation of the mercaptides because of their solvent effect but they have been found to be unnecessary for the operation of the process under the conditions described. The stocks treated, particularly if they are cracked stocks, usually contain a small amount of phenols, cresols, xylenols, etc., which aid in the separation of mercaptides.

In a typical operation of our process of regenerating KOH-methanol solutions, 100 volumes of 59 per cent aqueous KOH and 25 volumes of methanol were charged to the evaporator at a temperature of 248° F. to 294° F. The solution charged had a mercaptan number of 239. Methanol vapor was removed from the evaporator at a temperature of 154 to 160° F., 70 per cent of the methanol being taken off. The mercaptan number of the recovered methanol was 112. The aqueous caustic solution removed from the bottom of the evaporator was allowed to separate from the mercaptides and had a mercaptan number of only 4.8 with a trace of K₂S, indicating very slight decomposition of mercaptans in the operation. The separated mercaptide layer amounting to 5 per cent of the charged solution had a mercaptan number of 4530. No methanol was present in the mercaptides but the KOH equivalent was 0.6 pound per barrel of oil extracted.

In another example, the same spent caustic-methanol solution having a mercaptan number of 239 was charged to the evaporator maintained at 50 mm. Hg pressure absolute. The methanol distillate amounting to 81 per cent of the total methanol had a mercaptan number of only 9. The temperature in the evaporator was about 140 to 172° F. The recovered KOH solution withdrawn from the evaporator and separated from the mercaptides had a mercaptan number of only 1.2 and no detectable amount of K₂S. The mercaptide layer amounting to 5 per cent of the solution charged had a mercaptan number of 5100 with no detectable amount of methanol present. The KOH equivalent of the mercaptides was approximately 0.56 pound KOH per barrel of oil extracted.

Figure 3 shows the effect of methanol removal 75 on mercaptan number of a KOH solution con-

taining 59 parts KOH and 41 parts water, by weight, and 25 volumes methanol per 100 volumes of aqueous KOH, distillation at ordinary pressure being employed. When the amount of methanol was reduced to about 20 volumes, phase separation was observed which increased rapidly until the amount of methanol remaining was about 15 volumes, at which point nearly all mercaptans had separated as potassium mercaptides. Mercaptan number is expressed as milligrams of mercaptan sulfur per 100 milliliters of KOH solution in the aqueous phase.

Having thus described our invention what we claim is:

1. The method of removing mercaptans from a petroleum distillate which is higher boiling than gasoline and is within the kerosene to heater oil boiling range, which method comprises extracting said distillate at a temperature in the range of about 80° to about 100° F. with a solution of potassium hydroxide in water and methanol wherein the weight ratio of potassium hydroxide to water is in the range of 50:50 to 65:35 to give an aqueous potassium hydroxide solution which contains at least 50 but not more than 65 per cent potassium hydroxide by weight and wherein the methanol to aqueous potassium hydroxide volumetric ratio is greater than 15:100 but less than 60:100, separating aqueous potassium hydroxide methanol extract from extracted distillate and regenerating said extract by distilling at a temperature in the range of 130° to 300° F. to remove a part but not all of the methanol, without removing any substantial amount of water or mercaptans and without addition of water in liquid or vapor state, to reduce the methanol content below 15 volumes but not below 5 volumes per 100 volumes of aqueous potassium

5 hydroxide, separating the hot residual liquid from the distillation step into a concentrated aqueous potassium hydroxide phase and a potassium mercaptide phase, withdrawing said aqueous potassium hydroxide phase, adding condensed methanol thereto and returning the resulting aqueous potassium hydroxide methanol solution for further extraction of hydrocarbon distillate.

- 10 2. The method of claim 1 which includes the steps of separately withdrawing the potassium mercaptide phase, admixing it with sufficient water to produce a potassium hydroxide concentration of about 10 to 40 weight per cent, then separating a resulting oily mercaptan layer from dilute aqueous potassium hydroxide solution and concentrating said dilute aqueous potassium hydroxide solution for reuse.
- 15 3. The method of claim 1 wherein the amount of methanol remaining in the aqueous potassium hydroxide extract after the distillation step is in the range of 5 to 10 volumes per 100 volumes of aqueous potassium hydroxide solution.
